LINK CHAIN FOR A BRACELET OR THE LIKE

Emil Rodriguez, Corbera de Llobregat, Spain, assignor to
Jacoby-Bender, Inc., Woodside, N.Y., a corporation of
New York

Filed Jan. 14, 1965, Ser. No. 83,448

Term of patent 7 years

(Cl. D45—4)

FIG. 1.

FIG. 2.

FIG. 4.

FIG. 5.

FIG. 6.

FIG. 1 is a top plan view of a link chain for a bracelet, showing my new design;

FIG. 2 is a side elevational view thereof;

FIG. 3 is an end elevational view, on an enlarged scale, of the link chain of FIG. 1, taken from the right hand end of FIG. 1;

FIG. 4 is a top plan view, on an enlarged scale, of the top shell of one of the links from the body of the link chain of FIG. 1;

FIG. 5 is a side elevational view of the top shell of FIG. 4, taken from the right hand side thereof; and

FIG. 6 is an end elevational view of the top shell of FIG. 4.

I claim:

The ornamental design for a link chain for a bracelet or the like, as shown.
